UNITED STATES PATENT OFFICE

CATHERINE STOLZ, OF DAYTON, OHIO

LADY'S UNDERGARMENT

Application filed November 21, 1929. Serial No. 408,707.

This invention relates to new and useful improvements in a lady's undergarment.

It is the principal object of my invention to provide a one-piece undergarment, made of a fine, silk jersey, which consists of hose, bloomers, garters and brassière or vest. The garment is so constructed that it is durable, attractive, and especially adaptable for stage work.

10 It is another object of my invention to use elastic means to produce a garment which will fit snugly to the body of the person wearing it.

Another object of my invention is to provide in this garment, hose that extend much higher above the knee than do ordinary hose, so as to form tights.

Still another object of the invention is to provide an elastic strip between the top of 20 the hose and the bottom portion of the bloomers to serve as garter means for holding up the hose.

Other important and incidental objects will be brought out in the following specification and particularly set forth in the subjoined claims.

In the accompanying drawing illustrating my invention, Figure 1 is a front elevational view showing my combination undergarment, 30 consisting of the hose, bloomers and brassière fitted to a human figure. Figure 2 is a front elevational view, similar to Figure 1, showing a vest used instead of the brassière. Figure 3 is a side view showing the garter means, part of the hose, the lower portion of the bloomers and the ruffle trimming. Figure 4 is a back view of part of the garment showing the upper body portion and the back of the bloomers, and Figure 5 is a 40 back view of the garment disclosed in Figure 1.

Referring to the accompanying drawing for a detailed description of my invention, the numeral 1 designates the hose, which are 45 preferably made of a thin silk, full fashioned, and which extend approximately eight inches above the knee to serve the purpose of tights.

Fastened to the top edge of the hose 1, is a wide silk elastic band 2, as shown in Figure 50 3. The elastic band is preferably two inches

wide and provides garter means for the garment. The bloomers 3, formed with an elastic girdle section 4, in both the front and back of the bloomers, are attached to the elastic band 2 of the hose 1.

Attached to the bloomers, and extending over the top of the hose 1 and elastic band 2 are three rows of narrow lace ruffling, or any other suitable trimming.

Extending longitudinally from the top of the elastic bands 2 to the elastic girdle section 4, are four elastic strips 5, one strip of elastic running directly up the front of each bloomer leg, and one strip running directly up each side. It is this feature of the garment that provides the snug, tight fit that is so desirable, and especially so when the garment is used for stage work.

A piece of silk jersey 7 forms the connecting section between the elastic girdle section 4 and the brassière 6. (See Figure 1.) From the side seam of the brassière, extending across the back to the other side seam, is a preferably three inch elastic piece 6^a, shown in Figure 5. This piece of elastic 73 makes the brassière form fitting and disposes of shoulder strap means. A snapper opening 8 on the left under arm seam is provided for the purpose of getting into and out of the garment more easily.

By means of gathers along the side seams 9, and a longitudinal piece of elastic material 10 up the center portion, I provide a brassière of the uplift style.

If it is not desired to have a garment which includes the brassière portion, I have provided a plain vest 11 which forms the upper portion of the garment. The vest 11 is attached to the elastic girdle section 4 and has shoulder straps 12 which connect the front and back portion of said vest. (See Figure 2.)

While I use a fine silk jersey as the preferred material of which my garment is made, I do not want to limit myself solely to its use, as any other thin, silken material can satisfactorily be employed in its manufacture. I have also designated the use of an uplift type brassière, but, a straight type, or

any other type brassière may also be employed.

It is thus seen that my combination one-piece lady's undergarment, as above described, combines four separate pieces of clothing ordinarily worn by ladies, and it also combines usefulness, durability and attractiveness.

If it is not desired to include in the garment the brassière or vest portion, my garment can be constructed so as to consist of only the hose, bloomers and garters.

Having described my invention, I claim:

1. A lady's one-piece undergarment consisting of hose extending well above the knees, a bloomer portion, wide elastic bands serving as garter means connecting the bloomer portion to the upper edge part of the hose, an elastic girdle section integral with the bloomer portion to form the top thereof, elastic strips extending from the garter means to the elastic girdle section, and an upper body piece connected to the bloomer portion to complete the garment.
2. A lady's one-piece undergarment consisting of hose extending well above the knees, a bloomer portion, wide elastic bands serving as garter means connecting the bloomer por-

tion to the upper edge part of the hose, an elastic girdle section integral with the bloomer portion to form the top thereof, a brassière portion, and connecting material between the girdle section and the brassière to complete the garment.

3. A lady's one-piece undergarment consisting of hose extending well above the knees, a bloomer portion, wide elastic bands serving as garter means connecting the bloomer portion to the upper edge part of the hose, an elastic girdle section integral with the bloomer portion to form the top thereof, a brassière portion, and an elastic section forming the back of the brassière.

4. Bloomers for women's wear, consisting of an elastic girdle section and two downwardly extending leg portions, garter means and a plurality of elastic strips extending from the garter means to the elastic girdle section, one strip of elastic running directly down the front of each bloomer leg and one running directly down each side thereof, to effect a snug, tight fit between the bloomers and the wearer.

In testimony whereof I have hereunto set my hand this 18th day of November, 1929.

CATHERINE STOLZ.
